E. A. CARKIN.
QUICK RELEASE WHIFFLETREE.
APPLICATION FILED NOV. 23, 1908.

938,120.

Patented Oct. 26, 1909.

UNITED STATES PATENT OFFICE.

EDWIN A. CARKIN, OF MEDFORD, MASSACHUSETTS, ASSIGNOR, BY DIRECT AND MESNE ASSIGNMENTS, TO HARRIS B. MITCHELL, OF MALDEN, MASSACHUSETTS.

QUICK-RELEASING WHIFFLETREE.

938,120.

Specification of Letters Patent. Patented Oct. 26, 1909.

Application filed November 23, 1908. Serial No. 463,955.

To all whom it may concern:

Be it known that I, EDWIN A. CARKIN, of Medford, in the county of Middlesex and State of Massachusetts, have invented certain new and useful Improvements in Quick-Releasing Whiffletrees, of which the following is a specification.

This invention has for its object to provide a whiffletree adapted to quickly release the traces engaged with it, so that the horse may be quickly detached from the vehicle in cases of emergency.

The invention consists in the improvements which I will now proceed to describe and claim.

Of the accompanying drawings, forming a part of this specification,—Figure 1 represents a side elevation of a portion of a vehicle to which my improved whiffletree is applied. Fig. 2 represents a top plan view of a whiffletree embodying my invention. Fig. 3 represents a section on line 3—3 of Fig. 2. Fig. 4 represents a section on line 4—4 of Fig. 2. Fig. 5 represents a section on line 5—5 of Fig. 2. Fig. 6 represents a section on line 6—6 of Fig. 5.

The same reference characters indicate the same parts in all the figures.

My improved whiffletree is here shown as composed of a body portion 12 which is preferably made of wood, and ferrules 13 attached to the ends of the body portion and projecting therefrom, said ferrules being of metal and having their outer ends closed, and provided with recesses 14, adapted to receive the end portions of the usual harness traces 15. The preferred construction, whereby the recesses 14 are formed, is that shown in Fig. 4, each ferrule 13 having a head 16 which forms the inner side of the recess, and a bent arm 17 which forms the bottom and outer side of the recess. Two trace-engaging bolts 18 are provided, said bolts being movable lengthwise of the whiffletree and adapted to be projected into the recesses 14 to enter eyes formed in the end portions of the traces 15.

The inner side of each recess 14 is provided with a guide through which the corresponding bolt passes, the outer side of the recess being preferably provided with a socket 19, which receives and laterally supports the outer end of the bolt when the latter is projected, so that the bolt cannot be

bent or pulled from the recess by strain exerted on it by the trace.

Each bolt is automatically projected or held yieldingly in its trace-engaging position by means of a spring 20 which is located in a spring chamber formed within the ferrule 13 beyond the end of the body portion 12, as shown in Fig. 4. One end of the spring bears on the inner end of the bolt 18, and the opposite end of the spring bears on a plate or washer 21, which is supported directly by the end of the body portion 12.

Means are provided for retracting the bolts to withdraw them from the traces, said means being preferably as next described: 70 22, 22 represent bell crank levers which are fulcrumed at 23, 23 in the upper and lower walls of a shell 24 fitted in a recess formed in the longitudinal center of the body portion 12, the fulcrum pins 23 being located 75 within the space inside said shell and protected from injury thereby. Each lever has arms of unequal length, the shorter arms being within the shell 24 while the outer ends of the longer arms project from said shell 80 toward the rear side of the whiffletree, and are provided with slots 25, with which are engaged branches 26' of a flexible strap 26, or other suitable pull device adapted to extend from the whiffletree to the body 30 of 85 the vehicle. The vertical pivot bolt of the whiffletree, as shown in Figs. 3 and 5, passes through the shell 24 and not only holds the shell concealed within the recess, but also prevents the shell from being pulled out by 90 the strain on the pins 23 when the bell-crank levers are being operated.

27, 27 represent rods connected with the shorter arms of the levers 22, and extending therefrom through longitudinal passages 28 95 formed in the body portion 12 and through the springs 20. The outer ends of the rods 27 are suitably engaged with the bolts 18, the rods being adapted to retract the bolts from the recesses 14.

It will be seen that when the traces are engaged with the bolts 18, and a pull is exerted on the strap 26, the levers 22 are turned on their fulcrums, and are caused to move the rods 27 inwardly toward the center of 105 the whiffletree, and thus simultaneously retract the bolts 18 and release the traces 15.

Owing to the unequal length of the arms

of the levers 22, and the fact that the pull device is connected with the longer arms of the levers, the power exerted on the pull device is employed to good advantage in retarding the bolts.

The springs 20, besides automatically projecting the bolts, prevent rattling of the rods 27 and levers 22 in the whiffletree. Owing to the fact that the rods and levers are located mainly inside the whiffletree, the working parts are mainly out of sight, so that there is nothing objectionable in the appearance of the whiffletree. The location of the levers 22 at the central portion of the whiffletree obviates any necessity for extending the flexible pull devices to the end portions of the whiffletree.

Owing to the fact that the bolts are movable lengthwise of the whiffletree and crosswise of the traces, there is no liability of accidental displacement of the bolts by the strain exerted on them through the traces.

The rods 27 are preferably made of relatively stout wire, so that in case of the breakage of the body portion 12 of the whiffletree, said rods will prevent the whiffletree from becoming absolutely inoperative.

Owing to the described arrangement of

the bolts and recesses, improper connection of the traces to the whiffletree is impossible.

The described arrangement of levers, rods, and bolts enables the pull device or strap to be extended to any desired part of the vehicle, and either horizontally, upwardly or downwardly from the whiffletree.

I claim:

A whiffletree having a body portion formed with a recess and having longitudinal passages from said recess to the ends, a shell in said recess, the body portion and the shell having openings in alignment for a pivot bolt whereby the shell is locked in the recess, fulcrum pins crossing the space in said shell, levers mounted on said pins, trace-receiving recesses at the ends of the whiffletree, bolts movable lengthwise across said recesses to enter the eyes of traces inserted therein, and connections between said levers and bolts, said connections extending through the longitudinal passages of the body portion.

In testimony whereof I have affixed my signature, in presence of two witnesses.

EDWIN A. CARKIN.

Witnesses:

ARTHUR H. BROWN,
P. W. PEZZETTI.
